UNITED STATES PATENT OFFICE.

HENRY E. RICHARDS, OF OSWEGO, ILLINOIS.

STAY-ROLLER FOR SLIDING DOORS.

SPECIFICATION forming part of Letters Patent No. 229,185, dated June 22, 1880.

Application filed October 11, 1879.

To all whom it may concern:

Be it known that I, HENRY E. RICHARDS, of Oswego, in the county of Kendall and State of Illinois, have invented a new and valuable Improvement in Stay-Rollers for Rolling Doors; and I do hereby declare that the following is a full, clear, and exact description of the construction and operation of the same, reference being had to the annexed drawings, making a part of this specification, and to the letters and figures of reference marked thereon.

Figure 1 of the drawings is an elevation of the device. Fig. 2 is a vertical sectional view.

This invention has relation to stay-rollers for sliding doors for barns, cars, and other buildings or cases.

The nature of the invention consists in a stay-roller composed of a perforated hub and an inclined bearing-flange on its inner face, its outer face being concave and provided with a recess to receive washers therein, a screw-threaded bolt passing through said hub, and adapted to be secured to a door-sill, as herein-after shown and described.

In the accompanying drawings, the letter A indicates the sliding door, provided at the top with hangers of suitable construction, sliding on the guide of the top casing of the door-frame.

B represents the bottom stay-roller, constructed with a short perforated hub portion, a, and an inclined flange, b, the inner or projecting side of which is inclined at an angle approximating forty-five degrees, so as to bear against the outer angle of the lower edge of the door. This stay-roller is journaled on a straight threaded bolt, C, which is screwed into the sill D of the door-frame and forms the bearing of the roller. Being straight, there is no tendency to twist under the motion of the door, and the conical bearing of the flange allows a free and easy backward-and-forward motion without binding.

The flanged portion of the stay-roller B may be dished or concave upon its outer surface to accommodate the nut or head of the bolt and prevent said nut from projecting. The hub portion is long enough to provide a convenient seat for the door upon the portion b of the roller, and the lower bearing-surface of the door is formed to accommodate this construction.

The roller B is slightly concave or recessed on its outer face and provided in said concave face with a circular depression or recess, c, to receive the zinc washer i, which fits neatly therein and is covered by the washer e, immediately under the bolt-head.

The zinc washer i is placed in the depression c for the purpose of preventing the accumulation of rust in the bearings, and the concavity of the face of the conical flange assists in protecting said bearing from rain.

The object of this invention is to provide, in connection with a sliding door, a stay-roller for its lower edge, which will have its door-bearing b nearly parallel or only slightly inclined to the plane of the door, and its journal-bearings at right angles to said plane, this construction and form serving to prevent the journal from being bent or twisted under the swaying movements of the door and at the same time to keep the door properly stayed at its lower edge without binding.

The convex or bearing flange of this roller is so constructed that there will be but a slight portion of its surface in contact with the lower edge of the door, which is not designed to bear on the hub portion a, and may be beveled a little along its outer angle. This arrangement serves materially to lessen friction, and constitutes a cheap, durable, and simple device for the purpose described.

Having described my invention, what I claim, and desire to secure by Letters Patent, is—

The stay-roller consisting of the perforated hub portion a and inclined bearing-flange b on its inner face, its outer face being concave and provided with a recess, c, the washers e i, seated in said recess, and the screw-threaded bolt C, passing through said hub and adapted to be secured to a door-sill, the whole constructed, arranged, and combined to operate as shown and described.

In testimony that I claim the above I have hereunto subscribed my name in the presence of two witnesses.

HENRY EUGENE RICHARDS.
